MECHANICAL COLLATOR

Wilbur Evan Thomas, Bronx, N. Y.

Application July 27, 1943, Serial No. 496,304

5 Claims. (Cl. 270—58)

My present invention relates to an apparatus for collating sheet material, particularly paper sheets, and the like.

Although machines have heretofore been proposed for this purpose, they are generally of a relatively bulky and expensive type, and not suitable for ordinary office use where they would not be warranted, both from the standpoint of initial cost and of upkeep. Consequently in such situations collating of sheets has been performed by hand, with attendant slowness of operation and the occurrence of errors.

The principal object of the instant invention is the provision of a machine which will collate sheets much more rapidly and efficiently than can be done by hand, but which does not involve large outlays, either in initial cost or in upkeep. More particularly an object of the invention is the provision of a machine of this type of inexpensive, compact construction, requiring a minimum of attention.

A still further object of the invention is the provision of a collator which may be built of inexpensive and non-strategic materials.

A further object of the invention is the provision of an apparatus of the type referred to which operates with a high degree of efficiency.

A further object of the invention is the provision of a collator including means whereby the forward ends of the ejected sheets are automatically placed in contiguous relationship whereby they may be readily grasped by the hand of the operator.

My invention will be more fully understood and further objects and advantages thereof will become apparent when reference is made to the more detailed description thereof which is to follow and to the accompanying drawings, in which

Fig. 1 is a perspective view of a collator in accordance with the invention;

Fig. 2 is a longitudinal sectional view of the collator;

Fig. 3 is a sectional view taken on a line 3—3 of Fig. 2;

Fig. 4 is a sectional view taken on a line 4—4 of Fig. 2;

Fig. 5 is a fragmentary sectional view on an enlarged scale illustrating details of the construction;

Fig. 6 is a perspective view on an enlarged scale of an element of the apparatus;

Fig. 7 is a side elevational view of the apparatus illustrating its operation; and

Fig. 8 is a view similar to Fig. 7 illustrating the operation of a modified form of the invention.

Referring now to the drawings, there is shown a base member 10 suitably comprising a table supported from the floor on legs 12. Mounted on the table is the collator indicated at 14, and later to be described in detail. The table top includes a former 16 in which the collated sheets may be straightened and aligned prior to stapling. The table top also preferably includes a slot 20, through which the collated and stapled sheets may be dropped to be deposited in a hopper 22, supported below the table top.

Collator 14 comprises a plurality of superposed trays 24, each composed of a side member or rail 26 and a bottom member 28. Particularly where the trays are formed from wood, as is preferred, bottom member 28 may be rabbeted into the side rails 26, as illustrated particularly in Fig. 6. Interposed between the adjacent trays are spacer blocks 30 located preferably at each of the four corners of the trays and secured to the trays above and below by any conventional fastening means. As will be observed from an inspection of Figs. 1 and 2, the spacer blocks define closed end slots 32 between adjacent trays. The trays in any suitable number, as determined by the maximum number of sheets to be collated, are mounted in superposed relationship directly on the table 10 and may be secured thereto by bolts, screws, or the like. The spacer blocks on the uppermost tray support a cover plate 34, which projects laterally, preferably on both sides of the tray, to provide flanges 36 containing trackways 38. Extending longitudinally of the lowermost tray and secured thereto, or directly to the table, are strips 40 containing trackways 41, preferably similar to trackways 38 of the cover plate and in opposed relationship thereto. Trackways 38 and 41 may be of any suitable type, but as illustrated, preferably comprise dove tail slots.

Mounted in each tray is an ejector member 42 (see particularly Figs. 2, 4 and 6). Each ejector is composed of a divided bar 44, the ends of which project through opposite slots 32. The two sections of the bar 44 are connected by a pintle 46 on which is pivotally mounted a preferably T-shaped pusher member 48, including a head 50 carrying contact members 52. The latter are preferably formed of sponge rubber, felt, or similar materials which will exhibit traction forces on the sheets placed in the trays. Spacer blocks 30, in addition to closing the ends of the slots 32, serve as stops for the ends of bar 44, preventing it from moving out from either end of the tray.

The projecting ends of bars 44 of the several ejectors are connected as by mortising, as shown, or by any other suitable means, into slides 50 on opposite sides of the superposed trays. Slides 50 include tongues 52 on their upper and lower ends of a configuration to slidably fit in the tracks 38 and 41. Projecting from the slides are pins 54, adapted to be received within elongated slots 56 in levers 58, on opposite sides of the apparatus. Levers 58 are pivoted on any suitable part of the machine, for example, on rails 60, as indicated at 62. The lower ends of the levers are connected by a foot treadle 64 or other operating mechanism. The treadle is maintained in a normal forward position by a spring or the like 66.

A deflector plate 68 is preferably mounted directly on the table adjacent the lowermost tray. The deflector plate is inclined outwardly and upwardly and preferably extends upwardly at least half the height of the superposed trays. The deflector plate may include a recess 70 in its upper edge to promote grasping of the ejected sheets.

In the principal form of the invention, the rear end of the pile of trays may be closed in any suitable manner, as for example by an end plate 72 (see Figs. 2 and 4). In a modified form, the end plate may be omitted for a purpose later to be described.

In the operation of the apparatus described above, stacks of the different sheets to be collated are placed in the several trays with the pusher arm of the ejector member resting on the top sheet of each stack and with the ejectors in these retracted positions. Foot treadle 64 is then pressed rearwardly against the action of spring 66, causing forward movement of the slides 50 and of the ejector members. Due to the frictional engagement between pads 52 and the sheets, the top sheets of the stacks in the several trays are caused to move forwardly substantially simultaneously. As the sheets issue from the trays, the ends of the uppermost sheets sag downwardly and the lowermost are raised upwardly by sliding on the deflector plate 68, with the result that their outer ends approach each other to be readily grasped as a unit by the hand of the operator (see Fig. 7). The assembled sheets are then straightened and adjusted in former 16, stapled together and then deposited through slot 20 into hopper 22. Removal of pressure from treadle 64 causes return of the ejector members to retracted position, due to the action of spring 66, and the operation may then be repeated.

As will be readily understood from the above description of the construction and operation of the device of the invention, the sheets may be collated very rapidly and with a minimum of skill on the part of the operator. The apparatus is very simple in operation and construction and with minor exceptions may be composed of wood and similar non-strategic materials. The apparatus requires substantially no upkeep and its initial cost is low. The trays are preferably made of a size to take relatively large sheets, but the collator will operate equally as well with smaller sheets and, hence, only one collator need be required to handle ordinary situations. In lieu of the foot treadle, the collator can be operated by a hand lever or, if desired, may be motor driven by a simple adaptation, as will be readily understood.

In the modified form of the invention, as illustrated in Fig. 8, the superposed trays may be mounted in a central location on the table, and

deflector plates 68 supported at each end. In this instance the rear plate 72 is omitted, with the result that the collator operates in both directions of movement. That is, when the treadle is pressed rearwardly, sheets are ejected at the left hand side, as shown in Fig. 8, and when pressure is released on the treadle, the ejector member is moved in the opposite direction under the influence of the spring 66, and the sheets are ejected from the right hand side of the machine. In this form of the construction, employing two operators, substantially double production can be obtained without proportionately increasing the cost of the machine or the space required.

Having thus described my invention in rather full detail, it will be understood that these details need not be strictly adhered to, but that various changes and modifications will suggest themselves to one skilled in the art, all falling within the scope of the invention as defined by the subjoined claims.

What I claim is:

1. A collator comprising a base, a plurality of superposed trays including open front ends mounted thereon, each of said trays being adapted to support a stack of sheets, an ejector element in each tray having a portion to rest on the stack of sheets, means for causing simultaneous forward movement of said ejector elements to force said sheets from the open front ends of said trays, and a deflector member supported by said base and extending outwardly and upwardly in front of said trays from a point adjacent the forward end of the lowermost of said trays.

2. A collator comprising a plurality of superposed trays, spacers between adjacent trays defining slots extending substantially the length of the trays, ejector members in said trays, said ejector members including supporting means extending transversely of the trays, and a traction member pivoted thereon, slide means supported for reciprocation longitudinally of said superposed trays, and means extending through said slots connecting said slide means and said several ejector members for conjoint reciprocation.

3. A collator comprising a base member, a plurality of superposed trays mounted thereon, a cover for the uppermost tray, said cover projecting laterally beyond said trays, opposed tracks in said base and said laterally projecting portions of said cover member, elongated slots between adjacent trays and extending substantially the length thereof, ejector members in said trays, slide means supported in said opposed tracks for reciprocation longitudinally of said trays, means extending through said slots connecting said slide means and said ejector members, and means for reciprocating said slide members.

4. A collator comprising a plurality of superposed trays, each comprising side and bottom members, spacer blocks resting on said side members adjacent the ends thereof and defining elongated slots between adjacent trays, and an ejector member in each of said trays, said ejector members each comprising a divided supporting bar extending laterally across the tray with its ends projecting through said slots, said bar defining a central pivot portion, and a traction member including spaced contact members pivoted on said pivot portion.

5. A collator comprising a base member, a plurality of superposed open-ended trays mounted thereon, each of said trays being adapted to re-

ceive a stack of sheets, a cover for the uppermost tray, said cover projecting laterally beyond said trays, opposed tracks in said base and said laterally projecting portions of said cover member, elongated slots between adjacent trays and extending substantially the length thereof, reciprocable ejector members in said trays of a character to frictionally engage said sheets in both

directions of reciprocation of said ejector member to eject sheets from both ends of said trays, slide means supported in said opposed tracks, means extending through said slots connecting said slide means and said ejector members, and means for reciprocating said slide members with conjoint reciprocation of said ejector members.

WILBUR EVAN THOMAS.
